CONTAINER

Argyle Campbell, Glenview, Ill., assignor to Baxter Laboratories, Inc., a corporation of Delaware

Application June 30, 1937, Serial No. 151,250

3 Claims. (Cl. 215—37)

This invention relates to a container and more particularly to the type of container in which sterile fluids, such as intravenous solutions, are carried.

5 An object of the invention is to provide a container having improved sealing means which is effective in maintaining a vacuum and which may be easily and conveniently removed to prepare the container for withdrawal of its contents.

10 A specific object is to provide means for sealing a container employing a flexible sealing member and including suitable structure for clamping the flexible member against a plug or closure.

15 Other objects will appear as the specification proceeds.

The invention is illustrated in a preferred embodiment by the accompanying drawing, in which—

20 Figure 1 is a plan view of a container sealed according to my invention and with all parts in place; Figure 2, a plan view of the container as Figure 1, but with the cap and metal disk removed; Figure 3, a sectional view in elevation, 25 the section being taken as indicated at line 3 of Figure 1; Figure 4, a perspective view of the cap; Figure 5, a perspective view of the metal disk; Figure 6, a perspective view of the clamping ring; and Figure 7, a perspective view of the 30 flexible disk.

In the illustrations given, A designates a container; B, a plug or closure; C, a sealing member; and D, the means by which the plug and sealing member are held and confined.

35 The container A may be of any suitable type or size. As here shown it comprises a bottle having a neck 10 equipped with ribs or threads 11 extending therearound.

The plug B is seated within the opening of 40 neck 10 and preferably has a top flange 12 extending horizontally from the top of the plug and resting upon the top edge of the neck 10. A pair of openings 13 and 14, which may be of the shape shown in Fig. 3, extend through the plug, 45 and if desired, a glass tube 16 may be extended through opening 13, the head 16a of the tube resting within the shallow recess at the upper end of opening 13.

50 Preferably the plug B should be of rubber or other resilient material, and it is especially desirable that the portion of the plug about the annular flange 12 be of resilient material.

55 Over plug B, I place the flexible sealing member C which comprises a relatively thin disk or sheet of soft rubber or other similar material.

Disk C may be circular in form and is preferably coextensive with the top surface of plug B.

The means D by which the plug and sealing member are confined in place comprises a clamping ring 16 which has its lower edge engaged 5 under the beads 11 on the exterior of the bottle neck. The top of the ring is turned inwardly forming a horizontal flange 17 which extends over the edge portion of the flexible disk C. As shown more clearly in Figure 6 of the drawing, 10 the flange 17 has one area cut away, the cut 18 extending to the base of the flange and into side walls 19. The purpose of this cut is to expose the edge of the flexible disk at this area so that when the seal is to be broken, the edge of the 15 disk may be grasped by the fingers or suitable instrument and torn off.

Over the disk and clamping member, I prefer to place a metal disk 20 which is also circular and has its edge portion extending over the horizontal flange 17 of the clamping member. As shown in Figure 3, disk 20 is substantially coextensive with the annular flange 12 of the plug and sealing member C.

Over the metal disk 20 is placed the cap 21 which at its lower edge is engaged under bead 11 and has its side walls 22 extending adjacent the walls 19 of the clamping member. The top of the cap is cut away at the center leaving the horizontal flange 23 which has its inner peripheral edge extending inwardly of the outer periphery of the metal disk 20. If desired, a tear flap 24 may be provided. The metal of the cap may be comparatively thin so that with the aid of the flap, the metal may be torn away along the 35 side of the cap, thus permitting the cap to be removed.

To facilitate the tearing of metal through the use of the flap, sides of the cap may contain 40 weakened lines 25 which guide the lines of severance as the flap is pulled. To facilitate the removal of the cap after it has been severed through the use of the flap, I provide the small V-notch 26 in the flange 23 at a point preferably diametrically opposite the weakened lines 25. 45 With this construction the cap can be readily removed from the container after being severed by aid of flap 24. Spreading of the cap halves causes the flange 23 to tear beyond the bottom of notch 26 and the rear wall of the cap to 50 serve as a hinge. The particular type of cap which is employed in this embodiment is more fully described in Patent No. 2,108,583 which is issued from the copending application Serial No. 65,878, filed February 26, 1936. It is under 55

stood, however, that any suitable cap or holding means may be used for confining the members in place in the manner described.

The improved container may be used for various and many purposes, but since it is particularly useful for shipping and storing intravenous solutions while maintaining the solutions under partial vacuum, the operation of the device will be explained in connection with this use.

10. After the container A is filled with the solution, the plug B is placed in the neck and the disk C placed on top of the plug. When a suitable vacuum has been drawn, or produced the flexible disk will operate as a valve and will be drawn 15 tight against the plug to prevent the admission of air. Being resilient and flexible, the disk will be pulled downwardly into the top of openings 13 and 14, and slight depressions will appear on the top of the disk which mark the location of the 20 openings through the plug. Being thus drawn into the openings of the plug, the disk is maintained in tight engagement with the top edges of these openings so that there is less likelihood of air escaping into the container. In the case 25 of opening 13 where the glass tube 15 is used, the disk will be drawn slightly into the end of the tube and will make tight engagement with the top interior edge of the tube.

The seal formed as above described, however, 30 is not sufficient for an extended period of time, and a permanent seal is provided by clamping the edges of the flexible member to the plug and securing the whole structure firmly to the container. This is accomplished by placing the 35 clamping member 16 over the disk C and turning it to bring its lower edge into tight engagement with the under side of threads 11. It will be observed that the horizontal flange 17 of member 16 extends over the peripheral edge portion of 40 disk C and is disposed directly over the top edge of the container neck and annular flange 12 of plug B. As the clamping member 16 is turned down, this horizontal flange 17 presses the peripheral portion of disk C against the annular flange 45 12, and also causes the flange 12 to be pressed tightly against the top edge of the container.

To provide a more firm pressure against the edge of disk C, I place the metal disk 20 over the clamping ring, and then place the cap 21 50 over the disk 20. When the cap 21 is tightly turned into place, it will bear down firmly against the edge portion of metal disk 20, and this pressure is transmitted through horizontal flange 17 of member 16 to the edge portion of the flexible disk. In this way the soft flexible disk is 55 pressed into sure sealing engagement with the resilient annular flange of the plug. Also the plug is securely clamped to the container and held firmly in place. With this construction the 60 openings through the plug are doubly sealed, being sealed first through the engagement of the disk with the top edge of these openings, and secondly by having the edge portions of the disk clamped firmly to the plug flange.

65. When the contents of the container are to be used, the tear flap 24 may be grasped with the fingers and pulled to sever the front side of the cap. After spreading the sides of the cap it will fall free of the bottle, and the metal disk 20 is 70 then loose and may be removed.

Removal of the cap and metal disk, however, 75 does not release the vacuum, and the openings through the plug are still held by the double seal. To expose these openings so that the contents may be withdrawn, the operator grasps the flex-

ible disk C at the cut away area of member 16 where the edge is exposed and pulls this disk free of the container. It may often occur that the disk is so tightly held under horizontal flange 17 that it will not pull from under this flange but will tear. Whether the flexible disk tears or not makes little difference because it is always possible to remove the portion over openings 13 and 14 and permit the removal of the contents.

In the common use of such containers the 10 clamping ring 16 is left in place to maintain the plug in position during subsequent operations. Here it may be noted, however, that were it not for the cut 18 in member 16, it would be exceedingly difficult to remove the flexible disk since 15 the edges of the disk would then be tightly held under the flange with no place to obtain a start in removing this disk.

As shown in the drawing, I prefer to locate the two openings 13 and 14 in line with the cut 18 20 in member 16. By this arrangement, the user will be required to uncover opening 14 first, thus causing the air to enter this opening before it has an opportunity to enter the opening 13 which is farther removed from cut 18. Thus when 25 the container is standing in the position shown in Fig. 3, the air entering the container will be caused to enter through opening 14 and thus remain at the top of the container without passing through the liquid. If the air which enters 30 the bottle upon the breaking of the vacuum should pass through opening 13, it would be guided by the glass tube 15 to the bottom of the liquid and then allowed to bubble back through the liquid to the top of the container. Thus the 35 incoming air would be washed by the liquid and the liquid would be to some extent thereby contaminated.

In some instances, it may be desirable to have the air first enter through opening 13 as, for 40 example, if the bottle should be inverted, the air entering would pass through the tube and come to rest at the bottom of the bottle which now, after inversion, is the top, and thus the air would not be permitted to pass through the 45 liquid. To accomplish this purpose, the plug B would be rotated to bring the opening 13 closer to the cut 18 while opening 14 would be on the opposite side.

The important advantage of the cut 18 is that 50 it permits an alignment of the openings whereby the user can be caused, in the normal operation of opening the container, to uncover one opening before he uncovers the other. In this connection, it will be understood that there may be 55 any number of openings and that they may be arranged in any desired alignment.

It will be understood that while we have shown 60 telescoping cap members for clamping the plug in position, the cap members may, if desired, be equipped with threads for securing the cap to the neck of the container. It will be understood that many other forms of connecting the cap to the container neck may be employed without departing from the spirit of my invention. 65

The foregoing detailed description has been given for clearness of understanding only, and no unnecessary limitations should be understood therefrom, but the appended claims should be construed as broadly as permissible, in view of 70 the prior art.

What I claim as new and desire to secure by letters patent, is:

1. In combination with a container having a neck with its opening closed by a plug, said plug 75

having at least one opening therethrough, a clamping ring engaging said container and having an edge extending over said plug, a flexible sealing disk over said plug and having its peripheral edge portion extending between said clamping ring edge and said plug, a metal disk extending over said flexible disk and over said clamping ring edge, and a cap extending over said metal disk.

2. In combination with a container having an opening and a rubber plug closing said opening, said plug being provided with at least one opening therethrough, a flexible rubber sealing disk extending over said plug, a clamping member engaging said container and having its central area cut away, said member being provided with an integral endless peripheral portion extending around said container, the inner peripheral edge portion of said member extending over the edge portion of said sealing disk, said inner peripheral edge portion having an area cut away so as to

expose a part of the edge of said disk, and means secure with said container for bearing against said peripheral edge portion of said clamping member to maintain said rubber disk and plug in resilient engagement.

3. In combination with a container having an opening and a closure for said opening, said closure being provided with at least two passages therethrough, a flexible disk extending over said closure, a clamping ring engaging said container, said clamping ring being provided with an integral endless peripheral portion extending around said container and having an edge portion extending over said flexible disk and pressing it against said closure, said edge portion having an area cut away to expose a portion of the peripheral edge of said flexible disk, said cutaway edge portion being in alignment with said two passages.
